(57) **CLAIM**

The ornamental design for a game controller input bottom, as shown and described.

DESCRIPTION

FIG. 1 is a perspective view of a game controller input bottom showing my new design;

FIG. 2 is another perspective view of a game controller input bottom showing my new design;

FIG. 3 is a front view thereof;

FIG. 4 is a left view thereof;

FIG. 5 is a right view thereof;

FIG. 6 is a top view thereof; and,

FIG. 7 is a bottom view thereof.

The broken lines shown in the figures are for the purpose of illustrating portions of the game controller input bottom, which form no parts of the claimed design.
